SEWAGE DIGESTER

Clarence E. Keefer and Frank C. Wachter, Baltimore, Md., assignors to The Dorr Company, Inc., New York, N. Y., a corporation of Delaware

Original application June 9, 1931, Serial No. 543,131. Divided and this application November 16, 1931, Serial No. 575,448

7 Claims. (Cl. 72—13)

In the treatment of sewage and the like, the putreacible solids therein are separated therefrom in the form of a sludge, usually by sedimentation means. This sludge, as a step in its treatment to render it inert and odorless, is exposed to anaerobic bacterial action in a digester. This invention relates, among other things, to the construction of such a digester.

10 Sewage digesters comprise generally a sedimentation tank having driven mechanisms therein for impelling solids settling in the tank, to a sludge discharge outlet. These mechanisms are sometimes propelled through the medium of a vertical shaft in the digester which extends above the 15 digester cover to be driven by a suitable motor and gearing. A trussed bridge extends across the top of the digester tank for supporting the upper end of the vertical shaft and for supporting the driving motor mechanism.

20 With the present tendency toward beautifying sewage treating plants, it has become desirable to re-design the digesters and other tanks to eliminate therefrom the present unsightly truss construction. Therefore, one object of this invention is to meet that requirement.

25 However, to eliminate the trusses is not as easy as it may appear because it has entailed a redesign and re-arrangement of many of the digester elements. Accordingly, it has been necessary to provide means for supporting the inner edges of a substantially annular top; for instance, a center pier in the digester arranged to support a framework which, by means of hangers therefrom, in turn supports the inner ends of the digester roof-bearing members whose outer ends are supported by the digester wall.

30 The invention is broad enough to comprehend other features which comprise an arrangement of sludge-discharging mechanisms to readily conform to the above described roof design, and which also may comprise a housing for the pier, or extensions thereof, and the motivating elements of the sludge discharge mechanism. This part of the invention is being claimed separately herefrom.

35 The invention is illustrated in the accompanying drawings by showing one embodiment of our invention. This embodiment is used for illustrative purposes only for obviously many changes and modifications can be made therein without departing from the spirit of our invention as described herein and pointed out in the following claims. The embodiment chosen for this purpose is a sewage digester but the invention is capable 40 of uses, such as in clarifiers, so the use of the in-

vention is not intended to be limited to any specific field.

In the drawings, Fig. 1 is a vertical sectional view through our sewage digester, with parts broken away.

Fig. 2 is a horizontal sectional view taken along lines II—II in Fig. 1 while Fig. 3 is a vertical sectional view taken along lines III—III in Fig. 1. Fig. 4 is a plan view of the digester with parts broken away. Fig. 5 is a vertical sectional view taken along lines V—V in Fig. 4.

So that the invention may be more clearly understood the parts shown in the accompanying drawings will be described. The numeral 11 indicates a sewage digester. 12 indicates the side or boundary walls thereof and 13 its bottom. 14 indicates a sludge discharge hopper, preferably annular in shape having a sludge outlet 15. 16 indicates a shaft, column, or pier upstanding from the digester bottom. In larger sizes of tanks, a concrete pier is preferred but in smaller sizes a metal shaft can be used.

The manner of constructing and supporting the substantially horizontal digester top 17 forms an important part of this invention so it will now be described. The principle thereof is to have either the central pier 16 or an extension thereof, support a framework or spider. Hangers or slings depend from said framework and support inner ends of roof beams, the other ends of which find a bearing upon the digester walls 12. More particularly, the column or pier 16 is provided with an extension 18. In smaller sizes of digesters, the pier or shaft itself can extend above the digester top sufficiently to directly support the framework but in the embodiment shown the metal extension 18 is used. This extension is formed of various shaped beams 19, angle bars 20, and braces 21, as shown in Fig. 2, in any manner which gives the extension 18 sufficient strength. 22 indicates a reinforcing to withstand compressional strains put on the extension as will be described hereinafter. The top framework supported by the pier 16, or its extension 18, may be any framework suitable for sustaining the roof-supporting hangers which depend therefrom but in the present embodiment the frame comprises a substantially horizontal plate or cap piece on the extension 18 having a web piece 24 associated therewith. Secured to the web piece 24 are beams 25, and these beams are secured at the outer ends to webs 26. Stretching between the webs 26 and fin plates 27 carried by extension 18 and radially extending therefrom are compression beams or spreaders 28.

while 29 indicate hanger beams or straps or sling members depending from the webs 26 of the top framework, which are arranged to support the digester roof. A roof 30 may be provided over the top framework, and a housing 31 or side walls may be provided to enclose the pier extension 18, the top framework to make it more sightly and to protect it from the weather and to form a control house for the digester operating mechanism.

The digester roof is formed of beams 32 preferably radially arranged from the pier 16 having their outer ends resting on the digester boundary wall or walls 12. Adjacent to the inner ends of 15 the said top beams 32, they are secured to the hangers 29 whereby their inner ends may thus be supported. Some of the top beams 32 or extensions thereof, extend inwardly and terminate adjacent to the pier 16 to form a platform enclosing 20 the pier 16 and within the housing 31. These top beams 32 may have chordal bracing beams 37 for making the digester top structure more rigid. Over the top beams 32 is placed some top structure such as concrete 34. Concrete 35 25 may also be used in the housing 31 to encase the hangers 29 and plates 36 therebetween (Fig. 4). This substantially horizontal digester top may be arranged flush with the surrounding land, as shown in Figure 1, whereby the control house is 30 the only part of the digester observable projecting above the ground.

Having thus described the construction of our digester whereby the use of the usual trusses are eliminated, there will now be described the 35 arrangement of sludge-discharge mechanism adapted to cooperate with the central column or pier, since that pier serves such an important function in our digester tank design.

Solids settled by sedimentation in a digester 40 are usually impelled toward a central annular sludge discharge hopper or outlet, by means of substantially radial arms 40, carrying rakes 41, presenting a curved face to the sludge. In digesters, radial scum-breaking arms 42, may be 45 provided adjacent the top of the digester.

The radial arms 40 and 42, heretofore have been rotated usually by a supporting vertical shaft driven from above the digester. However, in the present design of digester, it is desired to 50 eliminate the central vertical shaft. In lieu thereof, this invention involves the use of a revoluble drum or sleeve 43 encircling the stationary column or pier 16. The drum may be apertured as at 44, in order to lighten it without sacrificing strength and it may be appropriately reinforced either longitudinally as at 53, or annularly, or both, to withstand thrust or compressional tendencies from the rake arms 40.

The drum is hung or depends from a support 60 adjacent its upper end from whence it is driven by a suitable motor and gearing located in juxtaposition thereto. That is to say, a motor 45, is suitably connected to a speed reducer 46, and drives a gear 47, such as a worm gear, meshing with a 65 co-acting bull or ring-gear 48, secured to the drum 43.

This ring-gear 48 is floated upon pier-supported anti-friction bearings, that is, the ring-gear is suitably mounted for rotation upon ball- or 70 roller-bearings supported on a casting 50, carried by the pier 16. If the tank be a digester and it

is desired to prevent gas from the digester creeping up along the drum 43, one or more water- or oil-seals may be provided such as an inner and outer water seal provided at 51 and 52 respectively.

It will thus be seen that by means of this invention a sewage digester is provided from which the present unsightly trusses have been eliminated. At the same time this design of covered digester permits its top-supporting center pier or 10 column not only to support the digester roof but to have the further functions of supporting the sludge-discharge mechanism and its motor devices which produces an efficient digestion apparatus which is not only highly efficient but reasonable in its cost of construction.

The application upon which this patent is based is a division of an original application filed June 9, 1931 bearing Serial No. 543,131 which matured into patent granted January 3, 1933 and which 20 on March 3, 1936 was reissued as Re. 19,878.

We claim:

1. A sewage digester comprising an enclosing wall, a substantially horizontal annular gas-tight top, beams for sustaining said top supported at 25 the outer ends by said wall, a central pier in said tank, and means associated with and deriving support from said pier and having depending members affording support for the inner ends of 30 said beams.

2. A sewage digester comprising a boundary wall, a bottom, a central pier upstanding from said bottom, a frame element supported from said pier above the tank, a plurality of tension members depending from said frame, a plurality of 35 beams supported by said boundary wall and secured to one of said tension members, and a substantially horizontal gas-tight top for the tank sustained by said beams.

3. A structure according to claim 2 in which 40 the substantially horizontal top is flush with the surrounding land.

4. The structure according to claim 2 in which said top is annular and encircles said pier, and a control housing adapted to enclose the central 45 opening of said annular top.

5. A sewage digester comprising a boundary wall, a bottom, a central pier upstanding from said bottom, a raftered frame supported from 50 said pier above said tank, substantially horizontal compression members extending between said frame and said pier, reinforcements embodied in said pier to withstand compression of said pier by said members, sling devices coacting with said frame, beams supported at one end from said 55 sling devices and at the other end by said wall, and a substantially horizontal gas-tight tank top sustained by said beams.

6. The structure according to claim 5 with the addition of chordal braces between said beams. 60

7. A covered tank adapted for use as a sewage digester comprising a boundary wall, a bottom, a substantially horizontal gas-tight top, a single central pier upstanding from said bottom and projecting through said top, a spider supported 65 from said pier above said top and means for supporting the central portion of said top from said spider.
